UNITED STATES PATENT OFFICE.

LESLIE W. CLAYBOURN, OF CINCINNATI, OHIO.

METHOD OF CURVING PRINTING-PLATES AND PRINTING-PLATES CURVED THEREBY.

1,318,967.

Specification of Letters Patent. Patented Oct. 14, 1919.

Application filed February 1, 1917. Serial No. 145,881.

To all whom it may concern:

Be it known that I, LESLIE W. CLAYBOURN, a citizen of the United States, residing at Cincinnati, in the county of Hamilton and State of Ohio, have invented certain new and useful Improvements in Methods of Curving Printing-Plates and Printing-Plates Curved Thereby, of which the following is a specification.

10 My invention relates to the art of bending printing plates and printing plates curved thereby, and is especially useful for curving printing plates employed in multi-color printing, in which a plurality of printing 15 plates are employed for printing different colors the impressions of which are intended to register with each other, but is also applicable to other printing plates.

The methods heretofore employed in bending printing plates have, in practice, caused a stretching of the printing surface, so that the printing surface of the bent or curved plate has been of a different size from its size in the flat, it being understood that the 25 printing plates are first formed flat. When employing the methods of curving printing plates heretofore in general use, the printing lines of the printing surface were disarranged during the curving, with the result that the curved printing surface laid out in plane differed from the said surface when in the flat, the impression of the curved printing surface having the spacings between its printing lines enlarged in the direction of the bending with relation to what they were when in the flat. The stretching or disarrangement mentioned of the printing surface resulted in poor registry or non-registry between the printing lines of the 35 various printing plates, for printing various colors in multi-color printing, and in other printing, for instance, book-work.

It is the object of the invention to avoid these objections.

45 The printing plates to which the invention particularly relates are curved printing plates arranged to be attached to plate cylinders in multi-color printing presses, or for printing books or other printing employing 50 printing plates or printing surfaces originally formed flat or substantially so and then curved to correspond substantially to the curvature of the plate-cylinder to which the curved plates are arranged to be secured 55 by suitable means.

Printing plates of this character usually comprise what is known as a printing-shell, being usually the electro-deposited metal, usually copper, deposited on the matrix in electro-plating, and a backing on which the printing-shell is supported. It is to be understood, however, that the invention is not limited to printing plates thus formed, but is applicable to printing plates having printing-surfaces regardless of how the same are formed. The same may be formed, for instance, by what is usually known as the stereotyping process.

The invention consists in so curving the printing plate by bending that its printing 70 size will be maintained; and, further, in so curving or bending the printing surface and its backing that distortion of the printing lines for printing purposes is avoided.

The invention consists further in heating 75 the elements of the printing plate and bending the same while heated with the ends thereof held against separating movement, whereby rearrangement of the material composing the backing of the printing plate is effected; 80 further in applying pressure to the curved printing plate elements; further, in applying said pressure as a progressively acting pressure along the line of curvature; and, further, in applying said progressively acting 85 pressure reciprocatingly.

The invention consists further in forming a printing plate having a printing surface of a material having a higher fusing point and a backing of a material having a lower 90 fusing point, and subjecting the elements of said printing plate to heat for rendering said backing material readily flowable under pressure with relation to the material of the printing surface, and while in such condition to combinedly curve the elements of the printing plate whereby the backing material is caused to shift with relation to the material of the printing surface so as to permit the curving but avoid the stretching of 100 the material of the printing surface; further to apply pressure, which may be a progressively acting pressure, along the line of curvature, and may be a reciprocating pressure along the said line of curvature, to the 105 curved elements of the printing plate.

The invention consists further in applying a cooling agency to the printing plate while the pressure is being applied; further, in providing said pressure under presence of a 110

cushion for the printing surface; further, in applying said pressure between substantially concentrically arranged elements of non-yielding material, one of which may be 5 a form corresponding to the intended curvature of the printing-plate; and, further, in applying said pressure upon an inner mold of rigid material having a pressing surface representing the sector of a cylinder whose 10 radius is approximately the same as the radius of the plate-cylinder on which the printing plate is to be employed, so as to form the inner surface of the printing plate concentric to the plate-cylinder; and, further, 15 in applying pressure to the elements of the printing plate while being heated in order that heat distribution may be equal throughout the area of the plate.

The invention consists further in bending 20 the elements of the printing plate simultaneously from both ends of the printing plate toward its middle.

The invention consists further in providing 25 a curved printing plate the lines of whose printing surface are maintained in the same relations as when the plate was in the flat; further, in providing a curved printing plate having a printing shell and a backing material which has yielded to the 30 resistance of the printing shell; and, further, in providing a novel curved printing plate curved from the flat having the printing lines of its printing surface maintained in their relations with the backing material.

An apparatus is illustrated in the drawings 35 by means of which the method may be performed and the printing plate curved, it being understood, however, that this apparatus is merely an exemplification of the employment of the method.

Figure 1 represents a side elevation of an exemplified machine employed in carrying out the invention, showing the mold-sections in actuated relation in full lines for curving 40 the printing plate, and showing the mold-sections in separated relations in dotted lines.

Fig. 2 is a plan view of the same showing the mold-sections in actuated relation.

Fig. 3 is a plan view of the same with the mold-sections in separated relations and showing a printing plate about to be curved.

Fig. 4 is an end elevation of the exemplified device partly broken away.

Fig. 5 is a cross-section of the device taken on the line 5—5 of Fig. 1, partly broken away, with the gage and presser-devices in raised relations.

Fig. 6 is a cross-section of the same on the same section-line, partly broken away, with the mold-sections open and the gage and presser-devices in active relation.

Fig. 7 is a side elevation of the exemplified device, partly broken away, and with the table shown in vertical longitudinal sec-

tion, showing the plate bent about the mold and one end of the flexible band released from the mold and shown partly laid back.

Fig. 8 is a plan view of a printing plate 70 about to be bent.

Fig. 9 is a longitudinal section of the same taken on the line 9—9 of Fig. 8.

Fig. 10 is a cross-section of the same taken on the line 10—10 of Fig. 8.

Fig. 11 represents a central vertical longitudinal section of the exemplified device, taken on the line 11—11 of Fig. 3, partly broken away, with the mold-sections separated and a printing plate on the flexible band about to be bent. 75

Fig. 12 is a similar view showing the mold-sections rolled partway toward each other and equally contacting the respective ends of the printing plate.

Fig. 13 is a central longitudinal section of 80 the bent plate as the same is received off the bending mold, the backing of the plate being provided with cross-ribs.

Fig. 14 is a similar section of the printing plate, when trimmed. 90

Fig. 15 is a cross-section of the bent plate whose backing is provided with longitudinal ribs.

Fig. 16 is a cross-section of an exemplified device for shaving the inner face of the 95 curved printing plate.

Fig. 17 is a cross-section of an exemplified device for trimming off the bearer portions of the curved plate.

Fig. 18 is a cross-section of an exemplified 100 device for trimming the ends of the curved printing plate after the same has its bearer portions removed.

Fig. 19 is a plan view, partly broken away, of a modified form of printing plate formed 105 with a printing layer, a backing layer, and an intermediate binder layer.

Fig. 20 is a longitudinal section similar to Fig. 12 but showing the layers of the modified form of printing plate; and, 110

Fig. 21 is an end view of the modified form of printing plate showing the layers united and the plate curved and trimmed.

In performing the improved method, the printing plate is preferably first formed 115 flat. An exemplified flat plate is shown at 21 having a printing surface 22. It may comprise a printing shell 23 and a backing 24. Its margins are preferably provided with bearers 25, 26, separated from the 120 printing surface by grooves 27, 28, the bearers 25 being exemplified as at the ends of the printing plate, representing its top and bottom when secured to the plate-cylinder in the printing press, the bearers 26 being exemplified as the side bearers. The bearers are useful for receiving the edge thrusts and the margin portions of the surface contacts in the formation of the printing plate, for 125 protecting the printing surface. 130

If desired, the rear face of the backing of the printing plate may be provided with recurrent depressions 29 exemplified in Fig. 13 as grooves forming ribs extending crosswise of the curvature of the plate, and in Fig. 15 as grooves forming ribs extending lengthwise of the curvature of the printing plate.

The printing shell is, in practice, formed 10 of electro deposited metal, usually copper, deposited on the matrix in electro plating, although it is within the purpose and scope of my invention that the printing surface may be formed by other means, either on a 15 printing shell or on the printing plate in its entirety.

When a printing shell is employed it is provided with a backing for supporting the same. In employing the invention this 20 backing is preferably of a material having a lower fusing point than the fusing point of the printing shell, in order that the printing plate elements may be subjected to heat to render the backing readily flowable under 25 pressure with relation to the printing shell.

As an exemplification but not as a limitation, it may be stated that the fusing point of the printing shell when of copper may be exemplified as approximately 1900 degrees 30 Fahrenheit. The backing material may be a mixture of lead, tin and antimony, in the proportion of ninety pounds of lead to five pounds each of tin and antimony, the fusing point of the mixture being approximately 35 600 degrees Fahrenheit.

The printing plate elements are subjected to heat of such degree and throughout such period of time as will effect a spongy condition of the backing material, that is, a heat 40 condition in the backing material, which is near its point of fusion and may, for example, be instanced as a temperature of 500 degrees Fahrenheit, to which the printing plate elements have been raised for a period 45 of five to seven minutes. Another example of the desired condition of the backing material may be instanced as a condition to render the backing material susceptible to indentation by the edge of a wooden block 50 pressed thereon by the hand. Any or all of these conditions may be present as indicating the desired state of the backing material when heated and for rendering the same 55 preferably pliable for the curving operation.

60 Other backing materials than that instanced may be employed as, for instance, gutta percha or other material, which is rendered pliable or bendable under heat and is stiff upon being cooled. The condition of the material desired will be one whereby the 65 backing material is permitted to readily flow under pressure with relation to the printing shell, so as to cause the moving or shifting action between the material of the backing 70 and the printing shell to take place in the

backing when curving the printing plate elements in order that the printing surface, when curved, will have its size maintained. Or, differently expressed, in order that the curved printing surface laid out in plane, as 70 exemplified for instance by the reverse of the impression on a sheet printed thereby, will be the same as said printing surface prior to curvature.

For accomplishing these objects the curving of the elements of the printing plate is effected by a progressive curving movement acting progressively equi-distantly to both sides of the median line of the plate, exemplified in the present instance as a simultaneous contact or end pressure upon both ends of the printing plate and a progressive curving movement upon the printing plate toward its middle.

Referring now to the exemplified device 85 employed in performing the improved method, means are exemplified for uniformly heating the elements of the printing plate throughout, the elements of the printing plate being preferably heated while under 90 pressure so as to cause uniform transference of the heat from the heating medium to the printing plate.

31 represents a table. This table is arranged to be heated uniformly throughout, 95 as by partially immersing the same in a bath 32 in a melting pot 33, suitable means being provided for heating the pot, shown as gas burners 34, formed for instance of perforated pipes under the pot fed from a suitable 100 source of supply and controlled by valves 35 discharging into gas and air mixers 36 for regulating the temperature applied to the melting pot.

The table is exemplified as supported in 105 the pot on suitable blocks 37 suitably secured with relation to the frame of the machine, for positioning the table.

The bath 32 is preferably of a material having a fusing point somewhat similar to 110 the fusing point of the backing material of the printing plate, and is rendered fluid by the heat to which the melting pot is subjected.

In the present exemplification the heat is 115 transmitted to the elements of the printing plate through the flexible band 41, herein-after mentioned, which may, for example, be a band of cold rolled steel, and a cushioning layer 42 between the elements of the 120 printing plate and the flexible band, which cushioning layer may be a sheet of paper. The printing plate elements are laid in upside down relation upon the flexible band, the printing surface being presented to the 125 cushioning layer when such cushioning layer is employed.

The frame of the machine is exemplified at 133 comprising a pedestal 44. The frame is shown as including the melting pot. 39

It is the intention to curve the printing plates on an arc of a cylinder to conform to the usual plate cylinders to which the curved printing plates are arranged to be attached by suitable locking means, for instance such as shown and described in Letters Patent No. 1,007,163, dated October 31, 1911, for improvements in printer's registering device.

10 In the present exemplification a pluri-part mold is employed about which the plate elements are curved, the printing plate elements being located between the flexible band 41 and said mold while subjecting the same to the bending or curving operation. The mold-sections are exemplified at 46, 47.

15 The ends of the band are exemplified as articulated by hinges 49, 50, to opposite ones of the mold-sections, at least one of the 20 hinges being releasable, as by releasing the pintles 51 from the straps of the hinges respectively on the mold-sections and flexible band.

25 The mold-sections are provided with arc faces 52, which, when the mold-sections are brought together, are continuations of one another for forming a composite mold having a bending face formed as a sector of the cylinder having a radius approximately the 30 length of the radius of the plate cylinder to which the printing plate is arranged to be secured, preferably making allowance for enabling a slight finishing cut to be taken off of the rear face of the backing of the 35 printing plate.

40 The curving of the printing plate is effected progressively along the curvature in lines parallel with the axis of the curvature equi-distantly from the median line of the plate parallel with said axis. Excess pressure upon the plate perpendicular to its printing surface is also preferably avoided.

45 In the exemplification these objects are accomplished by providing the mold-sections with gear-segments 54, at the respective ends of the mold-sections, which segments mesh with toothed racks 56 on the machine frame, so that when the mold-sections are moved toward and from one another their parallelism is maintained. This construction also insures that the distance between the hinges 49, 50 is maintained. Proper relative movement between the flexible band and the mold-sections with relation to each other and the 55 length of the flexible band, and proper spacing between the flexible band and the arc faces of the mold-sections are also maintained, this latter spacing being preferably approximately the thickness of the printing 60 plate, plus the cushioning layer 42, when the cushioning layer is employed.

65 Bearers 59, 60 are provided for the mold sections, the bearers 59 being shown on the mold-sections and the bearers 60 at the respective edges of the table, the bearers hav-

ing the purpose of insuring a proper space for the printing plate between the arc faces of the mold-sections and the flexible band.

70 Rests 62 are provided on the frame, upon which the mold-sections rest when in separated relations or when moved to the limit of one of their directions of movement.

75 In order to maintain the mold-sections in proper relative positions when connected, pins 64 on the respective mold-sections are arranged to be received in holes 66, on the opposite mold-section. A latch 68 on one of the mold-sections is arranged to be received by a catch 69 on the other mold-section for holding the mold-sections in connected relation when brought together.

80 In performing the method, the printing plate elements are preferably subjected to pressure during application of heat, and means provided to bear the plate upon the 85 heat-transmitting part in order to insure uniform distribution of heat throughout the printing elements. Means for accomplishing this are exemplified as comprising presser-feet 70 adjustable on bearings 71 lengthwise 90 of arms 72 and held in adjusted positions by set-screws 73. The arms are shiftable on their bearings 74 lengthwise of a rod 75 supported in brackets 76 extending from the frame of the machine. The arms and 95 presser-feet are so positioned as to rest upon the rear faces of the bearers 25, 26, of the printing plate elements when pressing the latter. The arms are held in down position by means of latches 77 arranged to engage 100 a holding bar 78 on the frame.

When a plate of large area is operated on, it is advisable to provide additional presser elements, acting upon the backing within the lines of the bearers 25, 26. Such additional presser elements are preferably of greater area than the presser feet 70 in order to contact a greater area of the backing of the printing plate elements to limit indentation by the same when the backing 110 is in heated condition. These latter presser means may, for instance, be presser shoes 80 on bearings 81 adjustable on an arm 82 and held in adjusted positions on the arm by set-screws 83, the arm being adjustable on 115 its bearing 84 lengthwise of the rod 75 and provided with a latch 87 coacting with the holding bar 78.

120 Uniform transmission of heat through the table and flexible band to the printing plate elements is thus insured. When the printing plate elements are in proper heated condition, the latches 77, 87, are released and the arms 72, 82, moved out of range of the mold-sections prior to operation of the mold-sections for curving the plate, as by swinging the same upwardly from the plate upon their bearings 74, 84. The arms 72, 82, may be counterweighted on the rod 75 by means 125 of counterweights 79, 89.

The printing plate is desirably so positioned with relation to the bending elements that contact between the bending elements and the respective edges of the printing plate 5 will be simultaneously effected along lines parallel to the axis of curvature of the printing plate when curved, which axis is either parallel with or perpendicular to the upright position of the printing lines, indicated at 88, on the printing plate, so that when the curved printing plate is arranged upon the plate-cylinder of the printing press, the printing face will be upright upon the printed sheet. For accomplishing this the 10 said edges, representing the top and bottom edges 85 of the printing plate have been trimmed parallel with each other and with the axis of the plate, and the side edges 86 of the printing plate have also been trimmed 15 perpendicular to the edges 85.

In order to position the printing plate, gages 91 are provided, the gages being adjustable lengthwise of arms 92 and held in adjusted positions by set-screws 93, the arms 25 92 being adjustable laterally and swingable on their bearings 94 on the rod 75, to move them out of range of the mold-sections during the bending operation. The arms are counterweighted by counterweights 99 for 30 raising the same, and with latches 97 for coacting with the bar 78 for holding the same in down position.

The arms 92 are arranged to be depressed by means of a handle 95 and are operable 35 independently of the arms 72, 82.

In positioning the plate, the plate is laid face down on the band and the arms 92 brought downwardly and latched so as to place the gages 91 above the band. The 40 side edge of the plate is then guided against the gages, whereby the axis of the plate, when curved, is brought into parallelism with the axes of the mold-sections. The back of the plate is provided with a mark 45 96 which coincides with the median line of the plate. The band is provided with a centering mark 98 with which the mark 96 is brought into registry for placing the ends of the plate equi-distantly from the ends of 50 the mold-sections.

The plate is positioned as stated, whereupon the presser means described are brought to bear upon the plate. Thereupon the gages 55 91 are raised by releasing the latches 97. The plate is subjected to the heat as hereinbefore described. When the plate or plate elements have been properly heated, the latches 77, 87, are released for raising the arms 72, 82, out of range of the path of 60 the mold-sections. It will be now apparent that when the mold-sections are moved toward each other, the mold-sections being subjected to equal movement, that equal end pressure or contact will be made simultaneously with both ends of the plate being

bent, (see Fig. 12), the curving action taking place in lines parallel with the median line of the plate, so that the printing lines will be in correct relation with the curvature of the plate.

When rolling over the mold-sections for bending the printing plate, the bending band will have a tendency to remain flat upon the supporting surface of the table and to bend on the arc of a circle as the ends of the 75 mold-sections, to which the ends of the band are secured, are raised from the table, thereby forming a space of uniform depth throughout the bearing surface of the mold between said bearing surface and the band, 80 in which the printing plate being formed is located.

In bending the printing plate, the ends thereof are preferably held against relative separating movement and the bending 85 accomplished while so held by the movement of said ends toward each other by a curving movement of the intermediate portions of the plate.

This is accomplished in the present ex- 90 emplification by a rolling movement of the mold-sections upon the printing plate, whereby the first contact between said mold-sections and the printing plate is made preferably simultaneously with the opposite 95 ends of the printing plate, as exemplified by a comparison of Figs. 11 and 12, such contact with said ends pinching said ends between the mold-sections and the flexible band sufficiently to maintain the ends of the 100 plate at its printing surface against separation, the movement of the mold-sections toward each other continuing until the flexible band and the printing plate elements thereon are curved about and upon the 105 mold-sections, the inner faces of the mold-sections meeting and the mold-sections being secured together by the latch 68 for forming a unitary mold, for instance as exemplified in Fig. 1. This movement of 110 the mold-sections to curve the printing plate is preferably a uniform and a comparatively rapid movement.

Upon the curving of the printing plate being accomplished, it is preferably subjected to a progressive pressure along the curvature, which pressure is preferably a reciprocating pressure and is instanced as a rolling pressure accomplished by a rolling back and forth of the united mold-sections 120 upon the table, whereby the printing plate is rolled between the flexible band and the mold-sections to insure a uniform conformity of the inner face of the printing plate with the curvature of the mold, this curvature being preferably a curvature approximating the curvature of the plate cylinder upon which the printing plate is to be secured, allowing preferably for a slight shaving to be taken off of the inner face of 130

the printing plate to remove any irregularities of surface which may be present due, for instance, to the heating and bending of the backing. The bearers 59, 60, prevent excess pressure upon the printing plate.

5 The initial pressure of the mold-sections upon the plate is preferably borne by the end bearers 25 on the printing plate.

If desired the printing plate may be subjected to a cooling agency during the curving operation or during the progressive pressure operation thereon, or during both said operations. When the printing plate is subjected to the cooling agency during 10 the curving operation, the cooling agency preferably acts upon the printing plate progressively with the curving operation so as to rapidly chill or set the material of the backing element of the printing plate as 15 20 the same is being curved.

The cooling agency is exemplified as a body 101 of fluid, for instance, water, in each of the mold-sections, which are formed hollow for the purpose, the water being fed 25 into the mold-sections by inlet pipes 102 and received from the mold-sections by outlet pipes 103, these respective pipes communicating with flexible pipes 104, 105, of desirable length and positioned to permit the 30 proper rolling of the mold-sections. Valves 106 may be employed to regulate the flow of the water and to regulate the temperature of the same in the mold-sections.

In the present exemplification of the 35 method, the heated backing element is in compressible condition, being for instance spongy, due to the heat application, that is, readily flowable under pressure with relation to the printing shell. The printing 40 shell during the curving operation retains its dimensions, so that the printing surface of the completed curved printing plate is the same as the printing surface before the curving. The spacings between printing 45 lines are maintained, so that a printed impression taken from the plate after being curved is the same as a printed impression taken from the printing surface when in the flat, or differently expressed, the printing surface of the curved plate laid out in plane is of the same dimensions as the printing surface when flat. A stretching of the 50 printing surface during curving is avoided. The material of the backing accommodates 55 itself to the curvature, the molecules thereof undergoing rearrangement due to the character of heating and curving action in the present exemplification, resulting in a curved printing plate in which the metal 60 is not buckled or strained, so that the inner face of the curved printing plate lies snugly throughout its area against the periphery of the plate cylinder, without hollow spots 65 thereunder.

65 Thus referring to Fig. 12, the ends of

the plate are perpendicular to its printing face. When the plate has been curved, these ends are parallel with the coincident radii of the sector of the cylinder formed by the plate. (See Figs. 7 and 13.)

70 The depressions 29 are exemplified as grooves for forming ribs 111. They may be formed in the backing prior to curvature in any desired manner, either while the backing is being made, or by cutting the same into 75 the backing after being made.

A slight shaving may, if desired, be taken off the inner face of the printing plate after curvature, which may be accomplished by laying the curved plate in a suitable machine 80 in a trough 115, with the printing face of the curved plate presented to the wall of the trough and with one edge of the plate against the longitudinally extending stop 116 and passing a rotary facing cutter 117 85 lengthwise of and parallel to its axis of rotation and to the axis of the plate across the inner face of the curved plate.

When the curving of the plate has been accomplished, the bearers 25, 26, are trimmed 90 from the plate, for instance in the line of the grooves 27, 28, between said bearers and the printing surface, which may be accomplished by passing the same over a table 120 95 along a trimming saw 121.

The edge of the plate is then provided with a suitable attaching face for securing the plate to the plate-cylinder, accomplished manually or by machine, as for instance by means of passing the same on a table 125 100 along the gage 126 and past a cutter 127 for shaping the edge of the plate, for instance, of bevel form, as shown at 128 when it is desired to attach the plate to the plate-cylinder by means of the fastening means 105 shown and described in Letters Patent No. 1,007,163, aforesaid.

The invention is, in Figs. 19, 20 and 21, shown applied to superposed plate elements comprising a printing layer 131, a backing 110 layer 132, and an intermediate binder layer 133, the binder layer being arranged to bind the printing layer and backing layer together by the action of the heat and pressure. This binder layer may be a layer, for 115 instance of tin foil, which has a fusing point less than the fusing point of either the printing layer or the backing layer, or the binder layer may be of other substance having a fusing point less than the fusing point 120 of the material of which the backing layer is composed.

As an example, it may be instanced that the printing shell is of copper, as hereinbefore described, the depressions in the rear 125 face of which are filled by a backing material composed of a mixture of lead, tin and antimony, as hereinbefore described, for forming the printing layer 131. The backing layer 132 may be composed of a mixture 130

of lead, tin and antimony, as hereinbefore described, and the intermediate binder layer may be a fusible alloy composed of lead, tin and bismuth in the proportion of one pound of lead to three-quarters of a pound of tin and one and one-half pounds of bismuth, the alloy melting at approximately 212 degrees Fahrenheit. If the backing material is composed of gutta percha or other material, the 10 binder layer may be composed of a suitable material having relative properties as hereinbefore described.

The top and bottom edges 185 of said layers and the side edges 186 of said layers are 15 trimmed on lines perpendicular to each other, respectively parallel with and perpendicular to the printing lines, so that said layers shall be curved with the axis of curvature parallel with or perpendicular to the 20 printing lines, as may be desired.

When employing the invention in connection with a printing plate comprising a fusible binder layer, the steps of the method are conducted similarly to the steps of the 25 method when employing a plate comprising a printing shell and a backing fixed thereto, as hereinbefore described, care being taken that the binder layer shall have become melted prior to the bending of the plate elements.

After the superposed layers are placed on the steel blanket and heat-applied thereto, the point of fusion of the intermediate fusing layer is watched and as soon as the fusing layer breaks down or melts and the backing layer becomes spongy, the mold-sections are rolled from both ends upon said layers and brought together and latched at their 40 separated ends, and then rolled upon the table.

The proximate faces of the printing layer and backing layer, when these faces are composed of metal, are preferably provided with an acid coating consisting of muriatic acid, 45 in order to aid fusion of the binder layer and unison of the printing layer and backing layer.

The printing plate thus formed has its inner face shaved, its bearers removed and 50 its ends provided with securing faces, similar to the steps described in connection with Figs. 16, 17 and 18, and it may also be provided with cross-depressions, similar to the cross-depressions shown in Fig. 13 or with 55 longitudinal depressions similar to the longitudinal depressions shown in Fig. 15.

The machine, printing plate, and melting means, herein shown and described, are not herein claimed, the same being shown, described and claimed in copending applications, respectively Serial No. 153,731, filed 60 March 9, 1917, Serial No. 153,732, filed March 9, 1917, and Serial No. 153,733, filed March 9, 1917.

Having thus fully described my invention,

tion, what I claim as new and desire to secure by Letters Patent, is:

1. The herein described curved printing plate having a printing shell and a backing of material having a lower fusing point than the fusing point of the material of said shell and bent with said backing at the inside while the temperature of said backing is near its fusing point. 70

2. The method of curving a printing plate 75 which consists in heating the printing plate, bending the printing plate while in heated state with its ends held against separating movement, and applying pressure to said bent printing plate. 80

3. The method of curving a printing plate which consists in heating the printing plate, bending the printing plate while heated with its ends held against separating movement, and applying progressively acting pressure 85 to said bent plate along its line of curvature.

4. The method of curving a printing plate comprising a printing surface and a backing material, which consists in heating said 90 printing surface and backing material to a point near the fusing point of said backing material, and combinedly bending, said printing surface and backing material while so heated. 95

5. The method of curving a printing plate comprising a printing surface and a backing material, which consists in heating said 100 printing surface and backing material to a point near the fusing point of said backing material, and combinedly bending said printing surface and backing material while so heated with the ends of said backing material held against separating movement.

6. The method of curving a printing plate 105 comprising a printing surface and a backing material, which consists in heating said printing surface and backing material to a point near the fusing point of said backing material, combinedly bending said printing 110 surface and backing material while so heated with the ends of said backing material held against separating movement, and then applying pressure to said curved plate along its line of curvature. 115

7. The method of curving a printing plate comprising a printing surface and a backing material, which consists in heating said 120 printing surface and backing material to a point near the fusing point of said backing material, combinedly bending said printing surface and backing material while so heated with the ends of said backing material held against separating movement, and then applying progressively acting pressure to said 125 curved plate along its line of curvature.

8. The method of curving a printing plate comprising a printing shell and a backing having respectively a higher fusing point and a lower fusing point, which consists 130

- in heating said shell and backing to render said backing readily flowable under pressure relative to said printing shell, and then combinedly bending said printing shell and backing into curved form.
9. The method of curving a printing plate comprising a printing shell and a backing, which consists in heating said shell and backing to render said backing readily flowable under pressure relative to said printing shell, then combinedly bending said printing shell and backing into curved form, and then applying pressure to said curved shell and backing.
10. The method of curving a printing plate comprising a printing shell and a backing, which consists in heating said shell and backing to render said backing readily flowable under pressure relative to said printing shell, then combinedly bending said printing shell and backing into curved form, and then applying progressively acting pressure to said curved shell and backing along their lines of curvature.
11. The method of curving a printing plate comprising a printing shell and a backing, which consists in heating said shell and backing to render said backing readily flowable under pressure relative to said printing shell, and combinedly bending said printing shell and backing into curved form while subjecting the surface of said backing distanced from said shell to the action of a cooling agency.
12. The method of curving a printing plate comprising a printing shell and a backing, which consists in heating said shell and backing to render said backing readily flowable under pressure relative to said printing shell, combinedly bending said printing shell and backing into curved form, and applying pressure and the action of a cooling agency to said curved printing shell and backing.
13. The method of curving a printing plate comprising a printing shell and a backing, which consists in heating said printing shell and backing to render said backing readily flowable under pressure relative to said printing shell, combinedly bending said printing shell and backing into curved form, and applying progressively acting pressure to said curved shell and backing along its line of curvature while subjecting the same to the action of a cooling agency.
14. The method of curving a printing plate comprising a printing shell and a backing, which consists in heating said shell and backing to render said backing readily flowable under pressure relative to said printing shell, combinedly bending said printing shell and backing into curved form, subjecting said backing to the action of a cooling agency, and applying progressively acting pressure to said curved shell and backing reciprocatingly along its line of curvature.
15. The method of curving a printing plate which comprises a printing surface and a backing, which consists in heating said printing surface and backing to render said backing readily flowable under pressure relative to said printing surface, combinedly bending said printing surface and backing into curved form between concentric surfaces one of which is rigid, and subjecting one of said surfaces to progressively acting pressure reciprocatingly along its line of curvature.
16. The method of curving a printing plate comprising a printing surface and a backing, which consists in heating said printing surface and backing to render said backing readily flowable under pressure relative to said printing surface, combinedly bending said printing surface and backing into curved form between concentric surfaces one of which is rigid and the other of which is cushioned with relation to said printing surface, and subjecting one of said surfaces to progressively acting pressure reciprocatingly along its line of curvature.
17. The method of curving a printing plate which consists in subjecting said printing plate to a heating agency presented to the printing surface of said printing plate while said printing plate is under pressure by pressures acting toward the back face of said printing plate for pressing said printing surface toward said heating agency, and bending said printing plate while in heated state into curved form.
18. The method of curving a printing plate which consists in subjecting said printing plate to a heating agency presented to the printed surface of said printing plate while said printing plate is under pressure by pressure toward the back face of said printing plate for pressing said printing surface toward said heating agency, bending said printing plate while heated into curved form, and then applying pressure to said curved plate.
19. The method of curving a printing plate which consists in subjecting said printing plate to a heating agency while said printing plate is under pressure for pressing the same toward said heating agency, bending said printing plate while heated into curved form, and then applying progressively acting pressure to said curved plate reciprocatingly along its line of curvature.
20. The method of curving a printing plate, which consists in heating said printing plate, bending said printing plate while heated with its ends held against separating movement, and rolling said printing plate between a form curved along the line of the desired curvature for said plate and a platen.
21. The method of curving a printing

- plate, which consists in heating said printing plate, bending said printing plate while heated with its ends held against separating movement and rolling said printing plate 5 between a form curved along the line of the desired curvature for said plate and a platen while said printing plate is held to said form by a relatively non-compressible sheet.
22. The method of curving a printing plate, which consists in heating said printing plate, bending said printing plate while heated with its ends held against separating movement and rolling said printing plate between a form curved along the line of the 10 desired curvature for said plate and a platen while said printing plate is held to said form by a relatively non-compressible sheet cushioned upon the printing surface of said printing plate.
23. The method of curving a printing plate comprising a printing shell and a backing which consists in heating said shell and backing to render said backing readily flowable under pressure relative to said shell, 15 combinedly bending said printing shell and backing into curved form between an outer flexible band and an inner mold, and applying pressure to said printing shell and backing while located between said flexible band and mold.
24. The method of curving a printing plate comprising a printing shell and a backing, which consists in heating said shell and backing to render said backing readily 20 flowable under pressure relative to said shell, combinedly bending said printing shell and backing into curved form between an outer flexible band and an inner mold, applying pressure to said printing shell and 25 backing while located between said flexible band and mold, and subjecting said combined printing shell and backing to reciprocating rolling pressure while between said flexible band and said mold.
25. The method of curving a printing plate comprising a printing shell and a backing, which consists in heating said shell and backing to render said backing readily flowable under pressure relative to said printing shell, combinedly bending said printing shell and backing into curved form between a flexible band cushioned against the printing surface of said printing shell and a mold, and applying rolling pressure to said 30 printing shell and backing through said flexible band and cushion.
26. The method of curving a printing plate comprising a printing surface and a backing material which consists in providing the back face of the backing material with recurrent depressions, heating said printing surface and backing material to a point near the fusing point of said backing material, and combinedly bending said printing surface and backing material while 35 so heated into the form of a sector or a cylinder, and then shaving the inner surface of said sector.
27. The method of curving a printing plate comprising a printing surface and a backing material which consists in providing the back face of the backing material with recurrent depressions, heating said printing surface and backing material to a point near the fusing point of said backing material, and combinedly bending said printing surface and backing material while so heated 40 into the form of a sector of a cylinder, shaving the inner surface of said sector, and then providing the ends of said sector with engaging faces for a securing means.
28. The method of curving a printing plate comprising a printing shell and a backing having edge bearers beyond the edges of the printing surface of said shell, which 45 consists in heating said shell and backing to render said backing readily flowable under pressure relative to said printing shell, combinedly bending said printing shell and backing into curved form, trimming off said 50 bearers, and then providing the ends of said curved plate with engaging faces for a securing means.
29. The method of bending a printing plate which consists in applying pressures 55 progressively thereon at points equi-distant from its median line.
30. The method of forming a curved printing plate which consists in superposing a printing layer, a backing layer and an intermediate binder layer, subjecting said layers to heat, to bending force, and cooling 60 said layers, in the order named.
31. The method of forming a curved printing plate which consists in superposing a printing layer, a backing layer, and an intermediate layer, heating said layers for rendering said backing layer spongy and fusing 65 said intermediate layer, bending said layers, and cooling said layers outwardly.
32. The method of forming a curved printing plate which consists in superposing a printing layer, a backing layer and an intermediate binder layer, heating said layers by heat applied at said printing layer, bending 70 said layers in superposed relation, and cooling said layers by a cooling agency applied at said backing layer.
33. The method of forming a curved printing plate which consists in superposing a printing layer, a backing layer, and an intermediate binder layer, subjecting said layers to heat for rendering said backing 75 layer spongy and fusing said intermediate layer, bending said layers in superposed relation, and cooling said backing layer.
34. The method of forming a curved printing plate which consists in superposing a printing layer, a backing layer and an intermediate binder-layer, subjecting said lay- 80

- ers to heat for rendering said backing layer spongy and fusing said intermediate layer, bending said superposed layers about a form while said backing layer is spongy, applying pressure throughout the surface of said plate at equal distances from the supporting surface of said form, and chilling the inner surface of said backing layer.
35. The method of forming a curved printing plate which consists in superposing a bending band, a printing layer, a binder-layer and a backing layer, subjecting said bending band to heat for rendering said backing layer spongy and fusing said intermediate layer, and bending said bending band about a form with said printing layer, binder-layer and backing layer interposed between said bending band and form, said form being cooler than said bending band.
36. The method of forming a curved printing plate which consists of superposing a bending band, a printing layer, a binder-layer and a backing-layer, bending said band and said layers about a form by bending force directed from opposite end portions of said layers toward the middle portion of said layers and about said form, and applying pressure throughout the area of said printing layer equi-distant from said form throughout said area.
37. The method of curving printing plates which consists in rendering the plate bendable by heat and then bending the plate by bending pressure applied at both ends of the plate toward its middle.
38. The method of curving a printing plate, which consists in applying bending pressure thereto from both its ends toward its middle portion.
39. The method of curving a printing plate, which consists in applying bending strains directed from the end portions of said plate toward its middle portion.
40. The method of curving a printing plate which consists in forming a printing surface layer, a backing layer, and an interposed binder-layer, subjecting said layers to heat for rendering the said printing surface layer and backing layer bendable and fusing said binder layer, applying bending force to said layers from both end portions toward their middle portion, applying rolling pressure to said layers on said form, cooling said plate, and trimming the edge of said plate.
41. The method of curving a printing plate comprising a backing which is a solid when unheated, which consists in transmitting the heat of a molten bath of material having a fusing point similar to said backing to said printing plate through an interposed support for the printing plate, bending the printing plate while heated into curved form, and then applying pressure to the curved plate.
42. The method of curving a printing plate comprising a backing which is a solid when unheated, which consists in transmitting the heat of a molten bath of material having a fusing point similar to said backing of the printing plate to the printing plate through an interposed support for the printing plate while the printing plate is under pressure, bending the printing plate while heated into curved form, and then applying pressure to the curved plate.
43. The method of curving a printing plate comprising a printing shell and a metal backing, which consists in applying the heat of a molten bath of metal having a fusing point similar to the metal of said backing to said printing shell and backing through an intermediate support while said printing shell and backing have pressure applied thereto for pressing said printing shell and backing toward said support, and then combinedly bending said printing shell and backing into curved form.
44. The method of curving a printing plate comprising a printing shell and a metal backing, which consists in applying the heat of a molten bath of metal having a fusing point similar to the metal of said backing to said printing shell and backing through an intermediate support while said printing shell and backing have pressure applied thereto for pressing said printing shell and backing toward said support, and then combinedly bending said printing shell and backing into curved form about a cooling mold.
45. The method of curving a printing plate comprising a printing shell and a metal backing, which consists in applying the heat of a molten bath of metal having a fusing point similar to the metal of said backing to said printing shell and backing through an intermediate support while said printing shell and backing have pressure applied thereto for pressing said printing shell and backing toward said support, combinedly bending said printing shell and backing into curved form, and applying rolling pressure to said curved printing shell and backing.
46. The method of curving a printing plate comprising a printing shell and a metal backing, which consists in applying the heat of a molten bath of metal having a fusing point similar to the metal of said backing to said printing shell and backing through an intermediate support while said printing shell and backing have pressure applied thereto for pressing said printing shell and backing toward said support, combinedly bending said printing shell and backing into curved form and applying rolling pressure to said curved printing shell and backing while said backing is subjected to the action of a cooling agency.
47. The method of curving a printing plate which consists in rendering the plate bendable by heat, applying bending stresses

from both end portions toward the middle portion of the plate about a form, and rolling said bent plate while on said form.

48. The method of curving a printing plate which consists in forming a printing layer and a backing layer, superposing said layers with an intermediate binder layer, subjecting said layers to heat and said binder layer to fusion, bending said layers about a form, causing rolling pressure upon said plate while about said form, and cooling said plate.

49. The method of curving a printing plate which consists in forming a printing layer, a backing layer, and an interposed binder layer, subjecting said layers to heat for rendering said printing layer and backing layer bendable and fusing said binder layer, applying bending force to said layers from both their end portions toward their middle portion, applying rolling pressure to said layers while on said form, and cooling said plate.

50. A curved printing plate having a printing shell, and a backing of material having a lower fusing point than the fusing point of the material of said shell and bent while the temperature of said backing is near its fusing point.

51. A curved printing plate comprising a printing shell, and a backing of material having a fusing point lower than the fusing point of the material of said shell, and curved while said backing material is at such temperature as to cause it to readily yield to the resistance of said printing shell.

52. A curved printing plate comprising a printing shell, and a backing of material having a fusing point lower than the fusing point of the material of said shell, the rear face of which is provided with recurrent depressions, and curved while said backing material is at such temperature as to cause it to readily yield to the resistance of said printing shell.

53. A curved printing plate comprising a printing shell, and a backing of material having a lower fusing point than the fusing point of the material of said shell, and curved while said backing material is at such temperature as to cause it to readily yield to the resistance of said printing shell, for maintaining all the parts of the printing surface of said printing shell in the same relations and of the same dimensions as before the curving thereof.

54. A curved printing plate having a printing shell and a backing of material having a lower fusing point than the fusing point of the material of said shell, said backing compressed progressively to greater extents toward its rear face while said backing is heated to approximately its fusing point to rearrange the molecules of said backing.

In testimony whereof, I have hereunto signed my name in the presence of two subscribing witnesses.

LESLIE W. CLAYBOURN.
